Primary Examiner — Manpreet Matharu*Assistant Examiner* — Keith Wilson(74) *Attorney, Agent, or Firm* — Thomas P. O'Connell;
O'Connell Law Firm(57) **CLAIM**

The new and ornamental design for a chair with sled base, as shown.

DESCRIPTION

FIG. 1 is a perspective view of a chair with sled base showing my new design;

FIG. 2 is a view in front elevation thereof;

FIG. 3 is a view in left side elevation thereof with the view in right side elevation being a mirror image of the view in left side elevation;

FIG. 4 is a top plan view thereof;

FIG. 5 is a bottom plan view thereof; and,

FIG. 6 is a view in rear elevation thereof.

The broken lines represent unclaimed features of the chair with sled base that form no part of the claimed design.
